(57) **ABSTRACT**

An integrated antenna includes a first antenna, a second antenna, and a third antenna. The second antenna is electrically connected to the first antenna. The third antenna is electrically connected to the first antenna and the second antenna, and the third antenna is integrated with the first antenna and the second antenna to form the integrated antenna. Lengths of the first antenna, the second antenna, and the third antenna are different.

INTEGRATED ANTENNA

**CROSS-REFERENCE TO RELATED
APPLICATION**

This application claims priority to Taiwan Application Serial Number 111144296 filed Nov. 18, 2022, the disclosures of which are incorporated herein by reference in their entireties.

BACKGROUND

Field of Invention

The present disclosure relates to a communication device. More particularly, the present disclosure relates to an integrated antenna.

Description of Related Art

With the development of technology, wireless communication technology is used in consumer electronics gradually. For enhancing ranges of consumer electronics, multi-frequency-band and multi-feed-in technology came into being, such that consumer electronics can be used in multiple frequency bands.

However, if multi-frequency-band and multi-feed-in technology is adopted, multiple antennas are needed. Owing to limiting space of consumer electronics, how to put multiple antennas into consumer electronics is an urgent need for industry to find out a solution.

SUMMARY

The foregoing presents a simplified summary of the disclosure in order to provide a basic understanding to the reader. This summary is not an extensive overview of the disclosure and it does not identify key/critical elements of the present disclosure or delineate the scope of the present disclosure. Its sole purpose is to present some concepts disclosed herein in a simplified form as a prelude to the more detailed description that is presented later.

The present disclosure provides an integrated antenna includes a first antenna, a second antenna, and a third antenna. The second antenna is electrically connected to the first antenna. The third antenna is electrically connected to the first antenna and the second antenna, and the third antenna is integrated with the first antenna and the second antenna to form the integrated antenna. Lengths of the first antenna, the second antenna, and the third antenna are different.

The present disclosure provides an integrated antenna includes a first antenna, a second antenna, and a third antenna. The second antenna is electrically connected to the first antenna. The third antenna is electrically connected to the first antenna and the second antenna, and the third antenna is integrated with the first antenna and the second antenna to form the integrated antenna. The first antenna, the second antenna and the third antenna operate in different frequency bands.

Therefore, based on the technical content of the present disclosure, the present disclosure integrates a plurality of antennas into single integrated antenna thereby reduce the size of the antenna so as to decrease the overall size of the product.

2

It is to be understood that both the foregoing general description and the following detailed description are by examples, and are intended to provide further explanation of the invention as claimed.

BRIEF DESCRIPTION OF THE DRAWINGS

The accompanying drawings are included to provide a further understanding of the invention, and are incorporated in and constitute a part of this specification. The drawings illustrate embodiments of the invention and, together with the description, serve to explain the principles of the invention. In the drawings,

FIG. 1 depicts a schematic diagram of an integrated antenna according to one embodiment of the present disclosure;

FIG. 2 depicts a schematic diagram of a front view of the integrated antenna shown in FIG. 1 according to one embodiment of the present disclosure;

FIG. 3 depicts a schematic diagram of another angle of view of the integrated antenna shown in FIG. 1 according to one embodiment of the present disclosure; and

FIG. 4 depicts a schematic diagram of an integrated antenna according to one embodiment of the present disclosure.

According to the usual mode of operation, various features and elements in the figures have not been drawn to scale, which are drawn to the best way to present specific features and elements related to the disclosure. In addition, among the different figures, the same or similar element symbols refer to similar elements/components.

DETAILED DESCRIPTION

To make the contents of the present disclosure more thorough and complete, the following illustrative description is given with regard to the implementation aspects and embodiments of the present disclosure, which is not intended to limit the scope of the present disclosure. The features of the embodiments and the steps of the method and their sequences that constitute and implement the embodiments are described. However, other embodiments may be used to achieve the same or equivalent functions and step sequences.

Unless otherwise defined herein, scientific and technical terminologies employed in the present disclosure shall have the meanings that are commonly understood and used by one of ordinary skill in the art. Unless otherwise required by context, it will be understood that singular terms shall include plural forms of the same and plural terms shall include the singular. Specifically, as used herein and in the claims, the singular forms "a" and "an" include the plural reference unless the context clearly indicates otherwise.

FIG. 1 depicts a schematic diagram of an integrated antenna 100 according to one embodiment of the present disclosure. As shown in the figure, the integrated antenna 100 includes a first antenna 110, a second antenna 120, and a third antenna 130.

For facilitating the understanding of the structure of the integrated antenna 100 of the present disclosure, reference is now made to both FIG. 2 and FIG. 3, which depict schematic diagrams of another angle of views of the integrated antenna 100 shown in FIG. 1 according to one embodiment of the present disclosure.

As shown in FIG. 1 to FIG. 3, with respect to structures, the first antenna 110 is electrically connected to the second antenna 120. The third antenna 130 is electrically connected

to both of the first antenna **110** and the second antenna **120**. In other words, the third antenna **130** is integrated with the first antenna **110** and the second antenna **120** to form the integrated antenna **100** of the present disclosure.

In this embodiment, lengths of the first antenna **110**, the second antenna **120**, and the third antenna **130** are different. Therefore, the first antenna **110**, the second antenna **120**, and the third antenna **130** operate in different frequency bands, for example, the first antenna **110** operates in 2.4 GHz, the second antenna **120** operates in 5 GHz, and the third antenna **130** operates in 6 GHz. In another embodiment, the integrated antenna **100** of the present disclosure can be used in WiFi wireless network with 2.4 GHz and 5 GHz, or can be used in WiFi-7 wireless network with 6 GHz, which operates in 5.95 GHz-7.125 GHz. Since the present disclosure integrates a plurality of antennas to form the integrated antenna **100**, the size of antenna can be reduced, so as to decrease overall size of product. In addition, since antennas are integrated into single integrated antenna, there is no need to use different molds to manufacture different types of antennas, thereby reducing the manufacturing cost.

In one embodiment, a first length L1 of the first antenna **110** rangers from 22 millimeters (mm) to 25 millimeters. In another embodiment, the first length L1 of the first antenna **110** can be 22.5 millimeters, 23 millimeters, 23.5 millimeters, 24 millimeters, or 24.5 millimeters.

In one embodiment, a second length L2 of the second antenna **120** rangers from 14 millimeters to 17 millimeters. In another embodiment, the second length L2 of the second antenna **120** can be 14.5 millimeters, 15 millimeters, 15.5 millimeters, 16 millimeters, or 16.5 millimeters.

In one embodiment, a third length L3 of the third antenna **130** rangers from 10 millimeters to 13 millimeters. In another embodiment, the third length L3 of the third antenna **130** can be 10.5 millimeters, 11 millimeters, 11.5 millimeters, 12 millimeters, or 12.5 millimeters. In one embodiment, a width L4 of the third antenna **130** rangers from 5 millimeters to 10 millimeters. In another embodiment, the width L4 of the third antenna **130** can be 6 millimeters, 7 millimeters, 8 millimeters, or 9 millimeters.

In one embodiment, a total length L of the integrated antenna **100** is a sum of the first length L1, the second length L2, and the width L4, and the total length L of the integrated antenna **100** rangers from 40 millimeters to 50 millimeters. In another embodiment, the total length L of the integrated antenna **100** can be 41 millimeters, 42 millimeters, 43 millimeters, 44 millimeters, 45 millimeters, 46 millimeters, 47 millimeters, 48 millimeters, and 49 millimeters.

Reference is now made to FIG. 1 to FIG. 3, the first antenna **110** can be a 2.4 GHz antenna, the second antenna **120** can be a 5 GHz antenna, and the third antenna **130** can be a 6 GHz antenna.

In one embodiment, the first antenna **110** and the second antenna **120** are disposed on a plane. For example, the first antenna **110** and the second antenna **120** are disposed on a XY plane. In addition, the third antenna **130** is perpendicular to the plane. For example, the third antenna **130** is located along Z axis. Therefore, the third antenna **130** is perpendicular to the XY plane.

In one embodiment, feed-in terminals of the first antenna **110**, the second antenna **120**, and the third antenna **130** are different. For example, a feed-in terminal **111** of the first antenna **110** is located below the first antenna **110** in the figure. A feed-in terminal **121** of the second antenna **120** is located below the second antenna **120** in the figure. A feed-in terminal **131** of the third antenna **130** is located below the third antenna **130** in the figure. In view of the above, the

integrated antenna **100** of the embodiment of the present disclosure can be a three-frequency-band and three feed-in antenna. Owing to the first antenna **110**, the second antenna **120**, and the third antenna **130** having their own feed-in terminal, independent feed-in terminal does not need a multiplexer at a rear end for processing, thereby reducing signal power loss and decreasing the cost of the entire device.

In one embodiment, the first antenna **110**, the second antenna **120**, and the third antenna **130** share a ground terminal. For example, the first antenna **110**, the second antenna **120**, and the third antenna **130** may share the ground terminal **140** which is a convergence of the three antennas in the figure. In this embodiment, current paths of the first antenna **110**, the second antenna **120**, and the third antenna **130** are shown in the figure, and the currents all flow into the ground terminal **140**. In another embodiment, the integrated antenna **100** further includes a layer structure **150**. The layer structure **150** is disposed on the XZ plane. The first antenna **110**, the second antenna **120**, and the third antenna **130** are disposed on the layer structure **150**.

In one embodiment, the first antenna **110** can be an inverted-F antenna, for example, a Planar Inverted F-shaped Antenna (PIFA). The second antenna **120** can be an inverted-F antenna, and the third antenna **130** can be a ring-shaped antenna. Reference is made to FIG. 1 to FIG. 3, the inverted-F antenna **110** and the inverted-F antenna **120** can be connected together, and disposed on the XY plane. In addition, the ring-shaped antenna **130** is disposed along Z axis, perpendicular to the inverted-F antenna **110** and the inverted-F antenna **120**, and electrically connected to the inverted-F antenna **110** and the inverted-F antenna **120**.

In one embodiment, the first antenna **110**, the second antenna **120**, and the third antenna **130** can be all made by metal. For example, the first antenna **110**, the second antenna **120**, and the third antenna **130** can be made by the same ironwork. Since the integrated antenna **100** can be made by the same ironwork after integrating, there is no need to used different molds to manufacture different ironworks, thereby reducing the manufacturing cost.

It is noted that the present disclosure is not limited to the structure as shown in FIG. 1 to FIG. 3, it is merely an example for illustrating one of the implements of the present disclosure, and the scope of the present disclosure shall be defined on the bases of the claims as shown below. In view of the foregoing, it is intended that the present disclosure covers modifications and variations to the embodiments of the present disclosure, and modifications and variations to the embodiments of the present disclosure also fall within the scope of the following claims and their equivalents.

FIG. 4 depicts a schematic diagram of an integrated antenna **100A** according to one embodiment of the present disclosure. Compared with the integrated antenna **100** shown in FIG. 1 to FIG. 3, the structure of the third antenna **130A** of the integrated antenna **100A** in FIG. 4 is different, which will be described in detailed as below.

As shown in the figure, the first antenna **110A**, the second antenna **120A**, and the third antenna **130A** can be inverted-F antennas. With respect to structures, the inverted-F antenna **110A** and the inverted-F antenna **120A** can be connected together, and disposed on the XY plane. In addition, the inverted-F antenna **130A** is disposed along Z axis, perpendicular to the inverted-F antenna **110A** and the inverted-F antenna **120A**, and electrically connected to the inverted-F antenna **110A** and the inverted-F antenna **120A**.

It is noted that the present disclosure is not limited to the structure as shown in FIG. 4, it is merely an example for

illustrating one of the implements of the present disclosure, and the scope of the present disclosure shall be defined on the bases of the claims as shown below. In view of the foregoing, it is intended that the present disclosure covers modifications and variations to the embodiments of the present disclosure, and modifications and variations to the embodiments of the present disclosure also fall within the scope of the following claims and their equivalents.

It can be understood from the embodiments of the present disclosure that application of the present disclosure has the following advantages. Since the present disclosure integrates a plurality of antennas to form each of the integrated antennas **100**, **100A**, the size of each of antennas can be reduced, so as to decrease the overall size of the product. In addition, owing to the first antennas **110**, **110A**, the second antennas **120**, **120A**, and the third antennas **130**, **130A** having their own feed-in terminal, independent feed-in terminal does not need a multiplexer at a rear end for processing, thereby reducing signal power loss and decreasing the cost of the entire device. Besides, since antennas are integrated into each of single integrated antennas **100**, **100A**, there is no need to used different molds to manufacture different types of antennas, thereby reducing the manufacturing cost.

Although the present invention has been described in considerable detail with reference to certain embodiments thereof, other embodiments are possible. Therefore, the spirit and scope of the appended claims should not be limited to the description of the embodiments contained herein.

It will be apparent to those skilled in the art that various modifications and variations can be made to the structure of the present invention without departing from the scope or spirit of the invention. In view of the foregoing, it is intended that the present invention cover modifications and variations of this invention provided they fall within the scope of the following claims and their equivalents.

What is claimed is:

1. An integrated antenna, comprising:

a first antenna;

a second antenna, electrically connected to the first antenna; and

a third antenna, electrically connected to the first antenna and the second antenna, and integrated with the first antenna and the second antenna to form the integrated antenna, wherein lengths of the first antenna, the second antenna and the third antenna are different; and wherein feed-in terminals of the first antenna, the second antenna, and the third antenna are different.

2. The integrated antenna of claim 1, wherein a first length of the first antenna rangers from 22 millimeters to 25 millimeters, a second length of the second antenna rangers from 14 millimeters to 17 millimeters, a third length of the

third antenna rangers from 10 millimeters to 13 millimeters, and a width of the third antenna rangers from 5 millimeters to 10 millimeters.

3. The integrated antenna of claim 1, wherein a total length of the integrated antenna rangers from 40 millimeters to 50 millimeters.

4. The integrated antenna of claim 1, wherein the first antenna comprises a 2.4 GHz antenna, the second antenna comprises a 5 GHz antenna, and the third antenna comprises a 6 GHz antenna.

5. The integrated antenna of claim 1, wherein the first antenna and the second antenna are disposed on a plane, and the third antenna is perpendicular to the plane.

6. The integrated antenna of claim 1, wherein the first antenna, the second antenna, and the third antenna share a ground terminal.

7. The integrated antenna of claim 1, wherein each of the first antenna and the second antenna comprises an inverted-F antenna, and the third antenna comprises a ring-shaped antenna.

8. The integrated antenna of claim 1, wherein each of the first antenna, the second antenna, and the third antenna comprises an inverted-F antenna.

9. The integrated antenna of claim 1, wherein the first antenna, the second antenna, and the third antenna comprise metal.

10. An integrated antenna, comprising:
a first antenna;
a second antenna, electrically connected to the first antenna; and
a third antenna, electrically connected to the first antenna and the second antenna, and integrated with the first antenna and the second antenna to form the integrated antenna, wherein the first antenna, the second antenna and the third antenna operate in different frequency bands; and

wherein feed-in terminals of the first antenna, the second antenna, and the third antenna are different.

11. The integrated antenna of claim 10, wherein the first antenna operates in 2.4 GHz.

12. The integrated antenna of claim 10, wherein the second antenna operates in 5 GHz.

13. The integrated antenna of claim 10, wherein the third antenna operates in 6 GHz.

14. The integrated antenna of claim 10, wherein a first length of the first antenna rangers from 22 millimeters to 25 millimeters, a second length of the second antenna rangers from 14 millimeters to 17 millimeters, a third length of the third antenna rangers from 10 millimeters to 13 millimeters, and a width of the third antenna rangers from 5 millimeters to 10 millimeters, wherein a total length of the integrated antenna rangers from 40 millimeters to 50 millimeters.

* * * * *
